HOT-TOP TABLE

Application filed January 10, 1929. Serial No. 331,595.

This invention relates to that type of electric heating devices known as hot tops.

An object of the invention is the provision of apparatus of this character which is especially adapted for use in dining and serving tables to keep dishes of food warm, also for use in stands or tables whereby surgeons and dentists may keep their instruments at a temperature suitable for operations.

Another object is to provide table hot top devices which are inexpensive to install, maintain and operate; and wherein the electric heating unit or units are readily accessible for inspection, repair or replacement.

Another object is to provide a dining table equipped with electric heating devices which are disposed in spaced relation from the edges of the table top to afford unheated outer portions upon which the diners may place their hands or elbows without discomfort.

Another object is to construct a table having in the top thereof a heating area or areas the upper surface of which is in the plane of the table top permitting a cloth to be spread smoothly throughout the entire top.

Other specific objects and advantages of the invention will appear in the following description.

The invention consists in the novel construction, adaptation and combination of parts hereinafter described and claimed.

In the accompanying drawing,—

Figure 1 is a vertical longitudinal section of a dining table with devices embodying our invention applied thereto; Fig. 2 is a fragmentary plan view of Fig. 1; and Fig. 3 is a diagrammatic view of the wiring for a five-unit heating system.

In said drawing, the reference numeral 5 represents, generally, the top of a table supported upon legs 6 and a skirting 7 depending from said top. Fitted within an opening 8 provided centrally of the top is a shallow metal casing 9 comprising side and end walls 10 which are provided along their upper edges respectively with out-turned flanges 11 which are welded or otherwise

firmly secured to the under surface of a cover 12.

A rabbet is provided in the frame 13 of the top which surrounds the opening 8 above referred to, said rabbet is of a size to accommodate the casing flanges 11 and the margins of the cover 12 thereabove so as to have the top surface of the latter flush with the corresponding surface of the table-top frame 13. The ledges provided by said rabbet bottoms serve to support the casing.

Let into apertures provided in the cover 12 is one or more imperforate plates 14, or "shields" as hereinafter termed, five being shown in Fig. 2, whose upper surfaces are also disposed in a plane common with the cover 12 and frame 13 of the table-top.

Said shields are formed of a material having a low-degree of heat conductivity with heat retaining characteristics—a known glass product being adapted to this purpose.

The bottom of the casing comprises a flat member 15 which is hingedly connected, as at 16, to one of the side walls 10 and is provided with a latch 17 engageable in a catch 18 secured to the opposite side wall. By thus connecting the bottom member of the casing to the side walls thereof, the bottom member is adapted to be swung downwardly to afford access into the interior of the casing.

Secured upon the bottom member 15 is a floor consisting of a sheet 19 of bakelite or other material of a relatively low conductivity for electricity; and 20 represents a lining of asbestos or the like for the casing side and end walls.

21 represent vent holes for the passage of air into and from the interior of the casing to obviate an excessively high temperature within the casing; the vent holes, moreover, are located above the level of the lower edges of the skirting 7, whence hot air escaping through said holes is diverted downwardly out of contact with diners who may be sitting about the table. Secured upon the floor 19 below the respective shields 14 is a plurality of electric heating units—illustrated as discs 23 in Figs. 1 and 2, and by resistance coils 23¹ in Fig. 3, which heating units may

be of any known suitable type. Said heating units are connected to a source of electric energy in any known manner as shown, for example, in Fig. 3, wherein the heating units (resistance coils 23') are connected in parallel with circuit wires A, B, the lead-in wires being denoted by a, b; S. denotes a switch, and R, a rheostat.

The construction of the illustrated embodiment of our invention and the manner of its operation will, it is thought, be understood from the foregoing description.

It may be pointed out, however, that the apparatus provides a means for furnishing a moderate heat to tables or the like to ensure food, theron being, kept in a most palatable condition; that the shields, through which heat is transmitted are at such a degree of temperature as to enable a cloth to be laid thereon beneath food-containing dishes which are to be kept warm; and, that, the diners are protected from the effects of the heat by means of the table skirting and, by, positioning the casing containing the shields within a surrounding frame portion 13 of a relatively poor heat conducting medium, against which the diners may rest their arms, and upon which frame, articles such as drinking glasses, etc., may be placed, without being materially affected by the heat obtaining above the respective shields.

The advantages of the invention, with respect to serving-tables, surgical instrument stands, and analogous applications, will be obvious from the above explanation regarding a dining-table.

What we claim is:

1. In a table-top, a case disposed therein in spaced relation with the edges thereof, said bottom member, electric heating units supported by said casing having a cover element provided with openings containing heat shielding plates, the top surfaces of said cover and the top surface of the table-top, said casing depending from the table-top and comprising side and end walls rigid with said cover, and said bottom member hingedly connected to one of the side walls, means for releasably connecting the bottom member to the other side wall, said walls being provided with vent holes, electric heating units supported by said bottom member below the respective shielding plates, and means to supply a current of electricity to said units.

2. In a table-top, a casing disposed therein, said casing having a cover element provided with openings containing heat shielding plates, the top surfaces of said cover and the top surface of the table-top, said casing depending from the table-top and comprising side and end walls rigid with said cover, and a bottom member hingedly connected to

side wall, electric heating units supported by said bottom member below the respective shielding plates, and means to supply a current of electricity to said units.

3. In a table-top, a casing disposed therein, said casing having a cover element provided with openings containing heat shielding plates, the top surfaces of said cover and plates being located in the same plane with the top surface of the table-top, said casing depending from the table-top and comprising side and end walls rigid with said cover, and a bottom member, said walls being provided with vent holes, electric heating units supported by said bottom member below the respective shielding plates, and means to supply a current of electricity to said units.

4. In a table-top, a casing disposed therein, said casing having a cover element provided with openings containing heat shielding plates, the top surfaces of said cover and plates being located in the same plane with the top surface of the table-top, said casing depending from the table-top and comprising side and end walls rigid with said cover, and a bottom member, electric heating units supported by said bottom member below the respective shielding plates, and means to supply a current of electricity to said units.

5. In a table-top, a casing disposed therein in spaced relation with the edges thereof, said casing having a cover element provided with openings containing heat shielding plates, the top surfaces of said cover and plates being located in the same plane with the top surface of the table-top, said casing comprising side and end walls and a bottom member, electric heating units supported by said bottom member below the respective shielding plates, and means to supply a current of electricity to said units.

6. In a table, the combination with the table-top, of a casing therein in spaced relation from its edges, a shield plate let into the top surface of the table-top, said casing depending from the table-top and comprising side and end walls rigid with said cover, and a bottom member hingedly connected to one of the side walls, means for releasably connecting the bottom member to the other side wall, said walls being provided with vent holes provided in the casing, and skirting de-

pending from the table-top in spaced relation from the casing to serve as a baffle for heated air emitted through said air vents.

7. In a table, the combination with the table-top, of a casing therein, a shield plate let into the top of said casing, vent holes provided in the casing, an electric heating unit, means for detachably securing said heating unit, interiorly, of the casing, and means to supply an electric current to said heating units.

Signed at Seattle, Washington, this 22nd day of December, 1928.
